UNITED STATES PATENT OFFICE

102,109

DESIGN FOR A PLATE OR SIMILAR ARTICLE

Bernard N. Kane, East Liverpool, Ohio, assignor
to The Hall China Company, East Liverpool,
Ohio, a corporation of Ohio

Application May 26, 1936, Serial No. 62,841

Term of patent 7 years

To all whom it may concern:

Be it known that I, Bernard N. Kane, a citizen of Great Britain, residing in East Liverpool, in the county of Columbiana and State of Ohio, have invented a new, original, and ornamental Design for a Plate or Similar Article, of which the following is a specification, reference being had to the accompanying drawing, forming a part thereof.

The figure is a top plan view of a plate or similar article showing my new design. The floral ornamentation is continued around the border or margin only of the plate shown.

I claim:

The ornamental design for a plate or similar article, as shown and described.

BERNARD N. KANE.
